UNITED STATES PATENT OFFICE.

GEORGE F. GALLAGHER AND THOMAS B. MOORE, OF ROCHESTER, NEW YORK,
ASSIGNORS OF ONE-THIRD TO HENRY GALLAGHER, OF SAME PLACE.

FURNACE.

SPECIFICATION forming part of Letters Patent No. 414,151, dated October 29, 1889.

Application filed January 16, 1889. Serial No. 296,474. (No model.)

To all whom it may concern:

Be it known that we, GEORGE F. GALLAGHER and THOMAS B. MOORE, citizens of the United States, residing at Rochester, in the county of Monroe and State of New York, have invented certain new and useful Improvements in Furnaces; and we do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

This invention relates to certain improvements in furnaces of the class for which Letters Patent No. 391,310 were granted October 16, 1888, to George F. Gallagher. In this class of furnaces passages are provided for conducting air from the outside to the rear of the fire-box and discharging the air thus heated into the fire-box.

To the above invention we have added our improvement by building an arch over the fire-box extending from the rear nearly to the front of the same, and taking the air from the ash-pit through the grate-bars in the usual way, as well as from the passages above mentioned, and also taking an auxiliary current of cold air up through the bridge-wall at the back of the fire-box, where it is discharged in the upper rear end of the fire-box, the combination of these drafts giving a more complete consumption of the particles of combustion.

We will now proceed to more definitely describe the manner in which we have carried out our invention.

In the drawings, Figure 1 is a longitudinal vertical section of our improved furnace. Fig. 2 is a transverse vertical section taken in the line $\alpha\alpha$ in Fig. 1. Fig. 3 is a horizontal section of the fire-box, and Fig. 4 is a partial front view of our improved furnace.

Referring to the drawings, $a\ a$ are the walls of the fire-box, in which is seated the boiler b .

c are the grate-bars, above which is the fire-box divided into sections $d\ d'$, and below the ash-pit e .

$f\ f'$ are the doors to the fire-box, and $f'\ f'$ the usual doors to the ash-pit. (See Fig. 4.)

The parts thus far described are of ordinary and well-known construction, and to these we have applied our improvements, as follows:

$g\ g'$ and $h\ h'$ are air-passages located above 55 the grate-bars and leading from the outside of the boiler to the rear of the fire-box, and then returning to the front of the fire-box and discharging the air in a highly-heated state at that point. The air from the passage g 60 coming through the door g^2 (see Fig. 3) is conducted through the passage g around the section d of the fire-box, and discharging into the front of the fire-box, as at g^3 , and the air passing through the door g^4 is conducted 65 through the passage g' around the section d' of the fire-box, and discharging at the opening g^5 . Directly under these passages $g\ g'$ are the passages $h\ h'$, having their inlet-doors h^2 and h^3 in the center of the front of the fur- 70 nace, and the passages extend, respectively, around the sections d and d' of the fire-box, and discharge the air in a highly-heated state at h^4 and h^5 . It will be seen that by this construction highly-heated air is fed to the front 75 of the sections $d\ d'$ of the fire-box on both sides, as clearly shown in Fig. 2.

To the rear of the sections $d\ d'$ of the fire-box, I have arranged the walls $j\ j'$, extending nearly to the arches $k\ k'$, and in the bridge- 80 wall m , I have arranged a channel or passage m' to allow a small current of cold air to pass from the ash-pit up between the bridge-wall and walls $j\ j'$, and is fed to the rear of the fire-box sections $d\ d'$ directly under the arches $k\ k'$, which extend over the fire-box sections 85 from the bridge-wall toward the front furnace-wall, but not entirely to such wall, leaving a space between the front ends of these arches and the front wall of the fire-box, through 90 which the heated air passes up between the top of the arches and the boiler to the combustion-chamber. It will be seen that the fire-box is supplied with highly-heated air from the passages $h\ g\ h'\ g'$. The draft is caused 95 to pass in the usual way up through the ash-pit; but a portion of this cold air in the ash-pit is drawn up through the back passages $m\ m'$ and discharged into the rear of the fire-box under the arches, thus supplying a lim- 100 ited but sufficient quantity of oxygen, which aids materially in the consumption of the

products of combustion, and at the same time maintains a current or draft forward to the points of discharge at the front of the arches. The highly-heated air from the passages $g\ h\ g'\ h'$ is also discharged at the front of the fire-boxes.

5 We claim—

1. In a furnace, air-passages, as shown, for conveying the air from the outside to the rear of the fire-box and discharging it therein in a heated state, such passages starting at the sides of the fire-box and returning at the center, substantially as shown and described.

10 2. The furnace having the ash-pit e , bridge-wall m , inner wall j , with passage m' between said walls and connecting the ash-pit and fire-box, and the arch k over the fire-box, substantially as and for the purpose stated.

15 3. In a furnace, the combination, with the

air-passages $g\ h\ g'\ h'$, arranged as shown, of 20 the bridge-wall m , inner wall j , with passage m' between, and the arch k over the fire-box, substantially as and for the purpose stated.

25 4. In a furnace, air-passages, as shown, for conveying the air from the outside to the rear of the fire-box and discharging it therein in a heated state, such passages starting at the center of the fire-box and returning at the sides, substantially as shown and described.

30 In testimony whereof we have signed our names to this specification in the presence of two subscribing witnesses.

GEORGE F. GALLAGHER.
THOMAS B. MOORE.
